[57] ABSTRACT

An accelerator for dry pipe sprinkler systems communicates with a dry pipe valve in such a system above and below the clapper thereof and acts to open a communicating passageway around said clapper upon a loss of air pressure in said dry pipe sprinkler system. The accelerator incorporates a pressure translator mechanism and a valve mechanism, both which prevent contamination from water in the sprinkler system from reaching the actuating parts of the accelerator.

ACCELERATOR FOR DRY PIPE SPRINKLER SYSTEMS

BACKGROUND OF THE INVENTION

1. Field of the Invention

This invention relates to a sprinkler system for fire protection purposes and more particularly to an accelerator for differential type automatic sprinkler valves used in such systems.

2. Description of the Prior Art 2,969,842.

Prior devices of this type usually incorporate valves for equalizing pressures on the opposite sides of the clapper of a dry pipe valve in a sprinkler system. See U. S. Pat. No. 2,969,842.

This invention improves the pressure translator and valve mechanisms of the prior art devices and insures against contamination of the accelerator mechanism by positively valving off the pressure translator during the operation of the accelerator.

SUMMARY OF THE INVENTION

An accelerator for dry pipe sprinkler systems is disclosed which includes a pressure translating mechanism and a spool type valve controlling a passageway around the clapper of a differential type sprinkler valve and a device responsive in operation to a loss of pressure in the sprinkler piping as translated by the pressure translator device to actuate said spool valve which, in turn, is arranged to open the communicating passageway around the clapper and close communication with the pressure translator device.

DESCRIPTION OF THE DRAWINGS

FIG. 1 is a fragmentary schematic view of a dry pipe sprinkler system having a dry pipe valve including the accelerator mechanism disclosed herein,

FIG. 2 is an elevational view of the accelerator mechanism, and

FIG. 3 is a side elevational view thereof.

DESCRIPTION OF THE PREFERRED EMBODIMENT

By referring to the drawings and FIG. 1 in particular, it will be seen that a fragmentary schematic view of a dry pipe sprinkler system has been illustrated to include a fluid supply source 10, a dry pipe valve 11 in communication therewith and incorporating a differential type clapper 12 which separates the interior 13 of the dry pipe valve 11 from an intermediate chamber 14 thereof. Sprinkler piping 15 extends from the upper portion of the dry pipe valve 11 and includes sprinklers 16 which are normally closed. The sprinkler piping 15 and the interior 13 of the dry pipe valve 11 are normally filled with compressed air so that the differential pressure thereof on the clapper 12 is sufficient to hold the same in closed position against the fluid supply 10.

An accelerator for rapidly equalizing the air pressure in the interior 13 of the dry pipe valve with the pressure in the intermediate chamber 14 is mounted immediately above the dry pipe valve 11 in a housing 17. The accelerator consists of a spool valve 18 which is in communication with the interior 13 of the dry pipe valve 11 by way of a pipe 19 and with the intermediate chamber 14 of the dry pipe valve 11 by way of a secondary pipe 20.

A pressure responsive release mechanism 21 acts to partially rotate a shaft 22 when released by a change in pressure as hereinafter described so that an arm 23 on the shaft 22 moves a spool in the spool valve 18. A

5 change in pressure for actuating the pressure responsive release mechanism is originated in a pressure translator 24 which communicates with the pressure responsive release mechanism 21 heretofore referred to.

10 By referring now to FIGS. 2 and 3 of the drawings the accelerator for dry pipe sprinkler systems may be seen in detail. In FIG. 2 the pressure translator 24 will be seen to comprise a cylindrical body member having openings at its upper and lower ends and formed of two

15 portions so as to position a flexible diaphragm 25 therebetween. A cup 26 rests on the diaphragm and engages one end of a coil spring 27, the other end of which is positioned in the upper end of the accelerator 24. Air tubing 28 communicates with the upper end of

20 the accelerator 24 and with a terminal block 29 and with a compensating vent 30 so that atmospheric pressure is normally present in the tubing 28 and the upper portion of the accelerator 24. The lower end of the ac-

25 celerator 24 communicates by way of a mounting fitting 31 with an orifice 32 in the spool valve 18 which has a chamber 33 therein in which a spool 34 is recipro- cally positioned. The spool 34 is normally urged toward the right end of the spool valve 18 by a spring 35. A

30 secondary orifice 36 in the spool valve 18 communicates with the chamber 33 and a third opening in the spool valve 18 also communicates with the chamber 33 and with a pipe 19 as hereinbefore described which ex- tends to the interior 13 of the dry pipe valve 11. A pipe

35 20 as heretofore described extends from the secondary orifice 36 in the spool valve 18 to the intermediate chamber 14 of the dry pipe valve.

It will thus be seen that when the spool 34 is in the position illustrated in FIG. 2 of the drawings where it 40 has been moved by the spring 35, the pipe 19 is in com- munication with the pipe 20 by way of the spool valve 18 and more specifically the chamber 33 therein.

It will also be seen that an enlarged valve section 37 of the spool 34 is in registry with the orifice 32 by way 45 of which the accelerator 24 normally communicates via the chamber 33 with the pipe 19 and hence the interior 13 of the dry pipe valve 11. In such normal position, the spool 34 is therefore in the left portion of the chamber 33 which is axial of the spool valve 18 and an extending end portion 38 of the spool 34 is positioned further to the left than that illustrated in FIG. 2 while the arm 23 is substantially vertical and its carrying shaft 22 rotated approximately an eighth turn clockwise.

It will also be seen that in such normal position, air 55 pressure from the sprinkler piping 15 and the interior 13 of the dry pipe valve 11 communicates with the lower portion of the accelerator 24 and moves the diaphragm 25 upwardly against the spring 27 so as to compress it in the upper half of the accelerator 24. Air

60 pressure resulting from such movement upwardly of the diaphragm is vented to atmosphere by the compen- sating vent 30 heretofore referred to which is a restricted air passageway requiring a time lapse to achieve compensation of the air pressure in the upper half of the accelerator 24, the air tubing 28 and the diaphragm case (not shown) in the pressure responsive release mechanism 21.

The operation of the pressure responsive release mechanism 21 is substantially the same as that disclosed in the aforementioned U.S. Pat. No. 2,969,842 and operation responsive to a drop in pressure starts with movement of a diaphragm in a diaphragm case which movement releases latches which, in turn, permit the shaft 22 to revolve.

The spool valve 18 will thus be seen to directly support and carry the accelerator 24 by way of the fitting 31 and the spool valve 18 is, in turn, carried on a mounting bracket 39, a right angular vertical extension 40 of which supports the shaft 22 as may be best seen by referring to FIG. 3 of the drawings. The bracket 39 is also attached to the pressure responsive release mechanism 21 so as to hold it in the assembly and is secured to the dry pipe valve 11 so as to position it in the manner illustrated in FIG. 1 of the drawings and heretofore described.

Operation

Under normal conditions fluid for the sprinkler system is present in the fluid supply 10 and held in check by the closed clapper 12 of the dry pipe valve 11. Compressed air is present in the interior 13 of the dry pipe valve 11 and the sprinkler piping 15 and the sprinklers 15 are closed. The air pressure communicates by way of the piping 19 with the interior of the accelerator 24 on the lower side of the diaphragm 25 and as hereinbefore described, this compresses the spring 27 and moves the diaphragm 25 upwardly therein from the position illustrated in FIG. 2. At the same time the pressure responsive release mechanism 21 is set so that its latches hold the shaft 22 in a position with the arm 23 thereof in substantially vertical position and therefore the spool 34 of the spool valve 18 to the left of the valve as seen in FIG. 2 of the drawings as is necessary to provide for communication between the orifice 32 and the pipe 19. The spool 34 simultaneously closes the communication between the pipe 19 and the pipe 20.

Upon the fusing of a sprinkler 16 the air pressure in the sprinkler piping 15 escapes thus lowering the pressure in the lower half of the accelerator 24 and permitting the spring 27 to move the diaphragm 25 downwardly to the position shown in FIG. 2 of the drawings. When this occurs a partial vacuum is created in the upper portion of the accelerator 24, the air tubing 28 and the diaphragm case in the pressure responsive release mechanism which results in movement of the diaphragm therein freeing the latches and permitting the shaft 22 to rotate responsive to the action of the spring 35 in the spool valve 18 moving the spool 34 to the right to the position seen in FIG. 2 of the drawings. The movement of the spool 34 opens the communication by way of the chamber 33 between the pipe 19 and the pipe 20 and thus permits the air pressure in the interior 13 of the dry pipe valve above the clapper 12 to immediately communicate with the intermediate chamber 14 below the clapper 12 whereupon the pressure is equalized. The fluid pressure in the supply pipe 10 can open the clapper 12 and the fluid will flow into the sprinkler system. Simultaneously with the opening of the communication between the pipes 20 and 19 the valve section 37 of the spool 34 of the spool valve 18 closes the orifice 32 which had permitted communication with the accelerator 24 and thus air pressure flowing through the pipes 19 and 20 and

the subsequent water or other fluid flowing therethrough upon the opening of the clapper 12 of the dry pipe valve 11 is blocked from communication with the accelerator 24.

5 It will thus be seen that the accelerator operates in a dry pipe sprinkler system to effect the rapid opening of the valve therein despite the presence of compressed air remaining in the system and more importantly the spool valve permits such rapid operation safely and effectively and at the same time prevents contaminating materials in the air and/or fluid supply of the sprinkler system from reaching the accelerator and/or the pressure responsive release mechanism.

10 15 Those skilled in the art will recognize that freedom of contamination of the essential parts of the accelerator insure the operation of the same when the sprinkler system operates.

15 20 Although but one embodiment of the present invention has been illustrated and described it will be apparent to those skilled in the art that various changes and modifications may be made therein without departing from the spirit of the invention.

I claim:

25 30 35 40 45 1. An accelerator for use in a dry pipe sprinkler system comprising in combination; a spool valve having at least one inlet port and first and second outlet ports, a spool therein being arranged to open communication between said inlet port and said first outlet port in a first position and movable so as to provide communication between said inlet port and said second outlet port in a second position, a pressure responsive release mechanism operatively engaging said spool so as to control the position thereof in said spool valve and an air pressure translator comprising a hollow body member, movable means in said hollow body member separating the same into two portions, one portion thereof being in communication with said first outlet port of said spool valve and the other portion thereof being in communication with said pressure responsive release mechanism, said inlet port being in communication with said dry pipe.

2. The accelerator of claim 1 and wherein said movable means in said hollow body member comprises a diaphragm thereacross.

3. The accelerator of claim 1 and wherein a spring is positioned in said hollow body member, said spring normally urging said movable means therein into one end thereof, said movable means being normally positioned in an opposite end thereof by air pressure from said dry pipe.

4. The accelerator of claim 1 and wherein air tubing establishes communication between said pressure translator and said release mechanism and a compensating vent communicates with said air tubing to establish atmosphere pressure in said tubing and connected parts of said release mechanism and pressure translator.

5. The accelerator of claim 1 and wherein a spring in said spool valve normally positions said spool thereof in a location opening communication between said inlet port and said outlet port with which said pressure translator communicates.

6. The accelerator of claim 1 and wherein there is a rotatable shaft in said release mechanism and controlled thereby, an arm perpendicular to said shaft and

engaged thereon, a slotted extension on said spool exteriorly of said spool valve, said arm being engaged in said slot, spring means for moving said spool upon actuation of said release freeing said shaft.
